CAMERA

Robert W. Moore, Chicago, Ill., assignor to Chicago
Aerial Industries, Inc., a corporation of Delaware

Filed Mar. 16, 1966, Ser. No. 1,487

Term of patent 14 years

(Cl. D61—1)

Fig. 1

The broken line showing of legible matter is for illustrative purposes only.

I claim:

The ornamental design for a camera, as shown and described.
